United States Patent Office

Des. 213,851

Patented Apr. 15, 1969

213,851

MICROFILM REAR PROJECTION VIEWER OR SIMILAR ARTICLE

William E. Karow, Los Angeles, and Lewis E. Simpson,
Wilmington, Calif., assignors, by mesne assignments, to
Leon Schwartz, Beverly Hills, Calif.

Filed Aug. 14, 1967, Ser. No. 8,247

Term of patent 14 years

Int. Cl. D16—04

U.S. Cl. D61—1

Fig. 1

Fig. 2

Fig. 3

FIGURE 1 is a left side, top and front perspective view of a microfilm rear projection viewer or similar article, showing our new design;

FIGURE 2 is a right side elevational view, to a reduced scale, the opposite side being substantially a mirror image thereof;

FIGURE 3 is a rear elevational view thereof, to the same scale as FIGURE 2.

A portion of FIGURE 1 is diagonally lined to indicate translucency.

We claim:

The ornamental design for a microfilm rear projection viewer or similar article, as shown and described.
